UNITED STATES PATENT OFFICE

161,831

BOLT TYPE FASTENER

John S. Grossman, Los Angeles, Calif.

Application July 17, 1948, Serial No. 147,641

Term of patent 14 years

(Cl. D10—5)

To all whom it may concern:

Be it known that I, John S. Grossman, a citizen of the United States, residing in the city of Los Angeles, county of Los Angeles, and State of California, have invented a new, original, and ornamental Design for a Bolt Type Fastener, of which the following is a specification, reference being had to the accompanying drawing, forming a part thereof.

Fig. 1 is a perspective view of the bolt type fastener, showing my new design, as viewed from the top and one end and one side thereof, and Fig. 2 is a perspective view of the bolt type fastener, showing the bottom, the other side and the other end thereof.

I claim:

The ornamental design for a bolt type fastener, as shown.

JOHN S. GROSSMAN.
